UNITED STATES PATENT OFFICE.

CHARLES WELINGTON NICKELL, OF JAMESPORT, MISSOURI.

HAY-STACKER.

SPECIFICATION forming part of Letters Patent No. 716,745, dated December 23, 1902.

Application filed December 20, 1901. Serial No. 86,670. (No model.)

To all whom it may concern:

Be it known that I, CHARLES WELINGTON NICKELL, a citizen of the United States, and a resident of Jamesport, in the county of Dade and State of Missouri, have invented a new and Improved Hay-Stacker, of which the following is a full, clear, and exact description.

The object of my invention is to provide a new and improved hay-stacker simple in construction and durable in operation and so designed that the load can be easily raised and can be lowered without the necessity of backing up the draft-animal used.

15 The apparatus comprises, essentially, three parts—to wit, a support or mast, a fork-carrying boom, and a power mechanism for raising and lowering the fork-carrying boom. These three essential parts are so designed 20 that they can be detached the one from the other, so that the entire apparatus can be readily transported to a meadow.

The invention consists of novel features and parts and combinations of the same, as will 25 be fully described hereinafter and then pointed out in the claims.

Reference is to be had to the accompanying drawings, forming a part of this specification, in which similar characters of reference indicate 30 corresponding parts in all the views.

Figure 1 is a rear end elevation of my improved hay-stacker. Fig. 2 is a side elevation. Fig. 3 is a partial section of a detail to be hereinafter described. Fig. 4 is a top plan 35 view of part of the power mechanism employed. Fig. 5 is a side elevation of the fork-carrying boom and its fork. Fig. 6 is a top plan view of the fork-carrying boom and its fork. Fig. 7 is a partial cross-sectional view 40 of a trigger employed for releasing the trip mechanism, whereby the fork is allowed to fall; and Fig. 8 is a general perspective view of the entire apparatus.

The support comprises a bed or base upon 45 which the mast is mounted. The bed in question is composed of a longitudinally-ranging timber 1, to the middle portion of which diverging strips 2 are securely bolted. From the strips 2 near the diverging ends thereof 50 the triangularly-shaped mast rises. This mast comprises the bottom member 3, recessed near its ends to receive the inclined side mem-

bers 4, which are recessed at their lower ends to receive the strips 2. The bottom member 3, the side members 4, and the strips 2 are 55 securely bolted or otherwise fastened together. To strengthen the mast, the side members 4 are tied together by a brace 5, held in place by bolts. At its middle a brace 5 is recessed to receive a post 6, bolted to the 60 brace 5 and provided at its upper end with a pintle 7, surrounded by a rigid sleeve 8, on which the boom removably rests and swings. A short tie 9 is bolted to the post 6, and to the said tie 9 an inclined brace 10 is secured 65 by means of a strap 11, of metal, bent to embrace the brace 10. A bolt is passed through the strap 11 and the tie 9, and bolts secure the strap and inclined brace together. The inclined brace 10 at its lower end is secured to 70 the longitudinally-ranging member 1, said longitudinally-ranging member being formed, as clearly shown in Fig. 2, with a slot which is designed to receive a bolt passing through the lower end of the brace 10, the parts being 75 securely held together by means of a nut screwed on the bolt. By reason of this arrangement the structure of the mast can be stiffened as desired by adjusting the brace through the medium of the slot and bolt. To 80 the ends of the tie 9 the members 12 of swinging outriggers or supporting-brackets are pivoted by bent metal straps 13. (See Fig. 1.) The remaining portions of the outriggers consist of horizontal members 14, secured to the 85 members 12 and pivoted to a bar 15, bolted to the bottom member 3 of the mast. It will be observed from Fig. 1 that the same slot-and-bolt connection is provided for the members 12 and 14 of the outriggers, as has been 90 described in connection with the inclined brace 10 and the longitudinally-ranging member 1 of the bed. By reason of this construction the hay-stacker can be conveniently carried to the field with the outriggers folded 95 against the longitudinally-ranging member 1 of the bed, set up in position, and the outriggers swung into the position shown in Fig. 1 to provide a broad and substantial support for the entire apparatus.

The fork-carrying boom includes in its construction two substantially parallel members 16 and the forwardly-extending members 19, secured and braced rigidly together, said

members 16 of the boom being secured together and carried by trunnions 17 of a sleeve 18, embraced by the beams 16. When the hay-stacker is in use, the sleeve 18, as clearly shown in Fig. 3, rests upon the sleeve 8, surrounding the pintle 7, and sustains the fork-carrying boom in such a manner that it can be readily swung from side to side or up and down. It is evident from this peculiar construction that the fork-carrying boom can readily be detached from the remaining portions of the apparatus simply by raising the sleeve 18 from the pintle 7. The divergent members 19 of the boom are rigidly fastened to the members 16 somewhat to the rear of the sleeve 18, said members 19 being tied together by a cross-bar 20. For the purpose of strengthening the connection between the members 16 and the members 19 I employ stiffening-rods 21, extending from the forward ends of the members 16 to the forward ends of the members 19. The forward ends of the members 19 are provided with apertures to receive the pivot-pins 22 on two of the tines 23 of the fork, whereby the fork is enabled to swing vertically independently of the entire boom, so that the load can be readily discharged without lowering the boom. The tines 23, as indicated in Fig. 1, are collectively screwed or otherwise fastened to a bar 24 and individually connected at their rear ends with vertically-ranging bars 25, forming each a right angle with its respective tine. The bars 25 are united by a cross-bar 26, to which an ear 27 is secured. By means of a pin 28, passing through the ear 27, the forward end of a slide 29 is held between the said ears. The slide 29 forms part of a trip mechanism, whereby the fork is caused to swing down by gravity in order to discharge its load. A yoke 30, secured to the rear end of the slide 29, glides on a pivoted bar 31, the forward movement of the yoke and slide being limited by a stop 32 on the bar 31, against which stop a pin 33, connecting the members of the yoke, is adapted to impinge. On its under side the bar 31 is provided with a catch 34 of triangular shape. The slide 29 is provided with a latch 35, comprising two cheek-plates fastened to the sides of the slide, in which cheek-plates a trigger 36, bent so as to form two parallel horizontal portions 36^a and 36^b, is mounted to swing. A rope 37 is fastened to the trigger 36 and passed over an idler 38. When the fork is in the position shown in Fig. 5, a backward pull on the rope 37 will first swing the trigger up and then draw the slide 29, and consequently the fork, back along the bar 31 until the latch 35 passes behind the catch 34. The fork will then appear in the position shown in Fig. 2. By pulling the rope 37 again the portion 36^a of the trigger will ride up the forwardly-extending incline of the catch 34 and raise the pivoted bar 31 until it lies against the slide 29. The weight of the hay will then be free to swing the fork down, thereby carrying the slide 29 forward

along the bar 31 until arrested by the stop 32, the latch 35 traveling to the forward end of the bar 31, as shown in Fig. 5. By means of ropes 39, secured to the sides of the fork, it is possible to swing the fork from side to side.

The rear end of the bar 31 is pivoted between the members of the forked end of a lever 40, fulcrumed in the forward ends of the beams 16. The rear forked end of the lever 40 is pivoted to a link 41, which is in turn pivoted on a lug 42, projecting from the sleeve 18. It is evident that the bar 31, the lever 40, and the link 41 form a system of compound levers, so that when the rear ends of the beams 16 are depressed the several elements of the system of compound levers will slightly depress the fork and so that when the rear ends of the beams 16 are elevated the fork in descending will be slightly tilted. Thus a fairly constant position of the fork is maintained within certain limits, whatever may be the up-and-down motion of the boom.

To complete the apparatus thus far described, a power mechanism of some kind is necessary whereby to raise and lower the boom. I employ a tackle comprising two pulley-blocks 43, held between the rear ends of the beams 16, and a single pulley-block 44, hooked to an eye 45 on the bottom member 3 of the mast. A hoisting-rope 46 is rove through the blocks 43 and 44 over the sheaves thereof in the well-known manner and over the sheaves of a pulley-block 47, hooked to any stationary part. One end of the rope is fastened to a stationary part of the pulley-block 44, and the other end is secured to a hoisting drum or windlass 48, loosely mounted on a shaft 49. The windlass and shaft can be made to rotate together or independently by means of clutch members 50, Fig. 4. When the clutch members are interlocked, the windlass and shaft turn together. When the clutch members are disengaged, the windlass rotates independently of the shaft. Since the windlass and shaft are to turn together only in raising the fork, I provide the shaft with a ratchet-wheel 51, engaged by a pawl 52, so that the shaft and windlass can turn together only in one direction. The pawl 52 is pivoted to a cross-piece 53, uniting two lugs 54 and 55, projecting, respectively, from the bottom member 3 of the mast and one of the inclined side members 4 of the mast. In order to disengage and interlock the clutch members 50, I fulcrum on the lug 54 a lever 56, secured to that clutch member which is splined on the shaft 49, the other clutch member being fast on the hoisting drum or windlass 48. The lever 56 is in turn operatively connected with one end of a bell-crank lever 57, fulcrumed on the lug 55, the other end of the lever being detachably connected by a link 58 with a cord or rod 59. As shown in Fig. 1, said cord or rod 59 is fastened to the short arm of a lever 60, fulcrumed on the bolt by which the members 12 and 14 of the outrigger are held together.

The cord or rod 59 is likewise connected by a link 61 with a brake-shoe 62, pivoted on the lug 55. The shaft 49 being turned in the proper direction by any available power, the hoisting drum or windlass 48 will likewise be turned, so as to wind up the rope 46, thereby drawing on the rear end of the beam 16 and elevating the fork. In order to allow the fork to descend, it is not necessary to reverse the power or to back up the draft-animal, but the lever 60 is swung so as to pull upon the rope or rod 59, whereby the bell-crank lever 57 will withdraw the clutch member of the shaft 49 from the clutch member of the windlass. The windlass will turn independently of the shaft 49 under the influence of the weight of the hay in the fork, so that the fork-carrying boom will descend as the rope is paid out. As the bell-crank lever 57 is operated, the brake-shoe 62 will be brought into contact with the hoisting drum or windlass 48, so as to regulate the speed of the boom. In order to interlock the clutch members 50 again, I coil about the shaft 49, between the ratchet-wheel 51 and the adjacent clutch member 50, a spring 63. It is evident that when under the influence of the bell-crank lever 57 the movable clutch member 50 is withdrawn from the windlass clutch member, the spring 63 will be compressed so that when the lever 60 is released the clutch members will be interlocked automatically by reason of the force exerted by the compressed spring 63. The shaft 49 is coupled by means of a universal joint 64 with a shaft 65 of a horse-power. By reason of this arrangement the horse-power can be placed in any convenient position.

The hay-stacker is to be carried to the field with the outriggers folded and the horse-power and fork-carrying boom detached therefrom. On reaching the meadow the mast will be placed in position and the outriggers spread in the manner indicated in Fig. 1. The shaft 65 of the horse-power will then be coupled to the shaft 49 and the sleeve 18 of the fork-carrying boom will be slipped over the pintle 7, carried by the post 6. The tackle is then arranged in proper position and the apparatus is ready for use. The fork being loaded, the shaft 49 is turned, the hoisting-drum 48 winds up the rope, the fork is raised to the desired elevation, the boom is swung by means of one of the rods 39 to the stack, the rope 37 attached to the trigger is pulled, and the hay is dumped on the stack by its own weight, as it causes the fork to swing on the pivots 22.

Having thus described my invention, I claim as new and desire to secure by Letters Patent—

1. A hay-stacker having a supporting structure; a boom mounted to swing horizontally and vertically on the supporting structure; a fork pivoted on the boom to swing independently thereof; a bar; a slide carried by the fork and adapted to glide on the bar in

response to the motion of the pivoted fork; a catch on the bar; a latch on the slide, adapted to be held by the catch in order to support the fork in raised position; means for releasing the slide-latch, in order to permit the fork to swing down by gravity; a lever fulcrumed on the boom and pivoted to one end of the bar; and a link pivoted to the lever and having a center of oscillation different from the center of oscillation of the boom.

2. In a stacker, the combination with a suitable framework, and a swinging boom, of a fork pivoted to said boom, a lever fulcrumed on the boom, a link pivoted to the lever and having an axis of movement located at a point to one side of the axis of oscillation of the lever, and operative connections between said lever and the pivoted fork to impart swinging movement to the latter in an opposite direction to the movement of the boom.

3. In a stacker, the combination with a framework, a swinging boom, and a fork pivoted to said boom, of a trip mechanism including a bar having a fixed point of resistance and carrying a catch, a slideable bar connected to the fork, and a latch movable with the slideable bar and adapted to be engaged with or disconnected from the catch.

4. A hay-stacker comprising a supporting structure; a boom mounted to swing vertically and horizontally on the supporting structure; a fork pivoted on the boom to swing independently thereof; a bar; a slide carried by the fork and adapted to glide on the bar in response to the motion of the pivoted fork; a lever connection between the bar and a center of oscillation off the center of vertical oscillation of the boom; and a trip mechanism for the bar and the slide, said trip mechanism serving to hold the slide in one position on the bar and to release the slide for the purpose of permitting the fork to swing down and discharge its load.

5. In a stacker, the combination with a framework, a swinging boom, and a fork pivoted to the boom, of trip mechanism including two bars arranged to have slideable movement with relation to one another, and one bar connected to the fork, and locking devices for restraining such relative movement of the bars.

6. The combination of a supporting structure and hay-stacking devices carried thereby, said supporting structure comprising a base having a longitudinal member and members divergent therefrom; a mast having a bottom member uniting the divergent members and fastened to the longitudinal member of the base; an inclined brace extending from the top of the mast to the forward end of the longitudinal member of the base; and pivotally-mounted supporting-brackets adapted in an inactive position to lie one on either side of the brace and adapted when horizontally swung to provide lateral supports for the supporting structure.

7. The combination of a supporting struc-

ture and hay-stacking devices carried thereby, said supporting structure comprising a base, a mast secured on the base and having two upwardly-converging members, a cross-piece uniting the said members, and a post rising from the cross-piece and adapted to carry the hay-stacking devices; and supporting-brackets pivoted to the mast and to the base, said supporting-brackets, when swung outwardly, serving as auxiliary supports for the hay-stacker.

8. In a stacker, the combination with a framework, a swinging boom, and a fork pivoted to said boom, of a trip mechanism including two bars arranged for relative slidable movement, one bar being connected to the fork, coöperative devices on the respective bars for having engagement with one another, and a line-controlled trigger carried by one of said bars and adapted to engage with the device on the other bar.

9. In a stacker, the combination with a framework, a swinging boom, and a fork pivoted to said boom, of a trip mechanism including two bars arranged for relative slidable movement, one bar being pivoted to the fork

and the other bar being connected to a lever which has a fixed point of resistance at one side of the axis of oscillation of the boom, and locking devices between the two bars to restrain them from relative slidable movement.

10. In a stacker, the combination with a suitable framework, a swinging boom, and a fork, of a tackle connected to the boom, a drum-shaft, a drum on which is coiled the cable of said tackle, a clutch arranged to make said drum fast with the shaft so as to allow the drum to turn idly on the shaft on the descent of the boom, means for restraining the drum-shaft from rotation in a backward direction, a clutch-shipping lever, and a brake-shoe operatively related to the drum and controllable by the clutch-shipping lever.

In testimony whereof I have signed my name to this specification in the presence of two subscribing witnesses.

CHARLES WELINGTON NICKELL.
